LIGHT SHADE

Sesto Chiarello, 2255 Market St., San Francisco, Calif.

Filed Oct. 1, 1964, Ser. No. 81,972

Term of patent 14 years

(Cl. D48—16)

I claim:

The ornamental design for a light shade, as shown and described.
